TRACK ALIGNING TOOL

Sam Difiglia, Kankakee, Ill.

Application July 1, 1937, Serial No. 151,503

1 Claim. (Cl. 254—44)

This invention relates to tools primarily adapted for aligning the rails of railroad tracks, and an object of the present invention is to provide a tool of this character which may be cheaply constructed and yet, at the same time, prove thoroughly efficient for the purpose designed.

A further object of the invention is to provide a tool of this character composed of several readily separable elements, whereby the elements may be separated for storage purposes, or quickly and easily assembled for use.

The invention, together with its objects and advantages, will be best understood from a study of the following description taken in connection with the accompanying drawings, wherein:

Figure 1 is a side elevational view illustrating the use of the invention.

Figure 2 is a top plan view of a stand forming part of the tool.

Figure 3 is a vertical sectional view through the stand and taken substantially on the line 3—3 of Figure 2.

Figure 4 is an end elevational view of the stand.

Figure 5 is a perspective view of a head member, and

Figure 6 is a perspective view of a handle or lever forming part of the invention.

Referring to the drawings by reference numerals, it will be seen that the tool consists, in the preferred embodiment thereof, of a stand indicated generally by the reference numeral 5, a head member indicated generally by the reference numeral 6, and a handle or lever indicated generally by the reference numeral 7.

The stand 5, which may be cast from metal or other suitable material, comprises a body having a rearwardly sloping inclined member 6 and an integral forwardly sloping inclined member 7, the members 6 and 7, at their lower edges, being sharpened as at 8 and 9, respectively, so as to penetrate the ground 10, as clearly shown in Figure 1, whereby the stand is held against "creeping".

The forwardly sloping inclined member 7 of the stand is bifurcated, as at 11, and the upper end of the member 6 of the stand is braced with respect to the member 7 of the stand, as at 12, and is also bifurcated or notched, as at 13, so as to accommodate, together with the notch or bifurcation 11, the aforementioned head 6 in a manner clearly shown in the drawings.

At the inner ends of the notches 11 and 13, the members 7 and 6, respectively, are beveled as at 14 and 15, respectively, so as to allow for maximum swinging movement of the head 6. Rising from the upper portion of the member 6 of the stand 5 are flanges 16 provided with slots 17 and notches 18 in the lower edges of the slots,

whereby to accommodate a transverse pivot pin 19, which extends through an intermediate portion of head 4. The head 4 is provided with a rail-engaging end 20, the rail-engaging face of which is corrugated, as at 21, or otherwise so provided so as to prevent slipping of the head when engaged with the base flange of the rail 22, as shown in Figure 1.

The upper end of the head 4 is provided with a socket 23 which accommodates the rectangular end portion 24 of the aforementioned lever or handle 7.

In use, the stand 5 is placed at one side of the rail 22, between adjacent ties 25, and upon placing a pin 19 in selected, aligned slots 18, the operator pushes or pulls on the lever or handle 7 to rotate the head 4 in a counter-clockwise direction, so that with the end 20 of the head engaging the base flange of the rail 22, lateral pressure will be placed on the rail to shift the same laterally in the proper direction to parallel the rail 22 with its companion rail and also to align the rail section 22 with the next adjacent rail, as will be understood by those skilled in the art to which this invention relates.

It is thought that a clear understanding of the construction, utility and advantages of a tool of this character will be had without a more detailed description.

Having thus described the invention, what is claimed as new is:

In a track aligning tool of the character described, a stand comprising an inclined body member tapering toward its lower edge into a sharp ground-penetrating edge, said body member having integral therewith intermediate its upper and lower ends a forwardly sloping inclined body portion, the first mentioned body member at its upper edge, and said forwardly sloping inclined body portion, respectively, being notched to accommodate a tool-head, said forwardly sloping inclined body portion having its lower edge at opposite sides of the notch sharpened to present ground-penetrating edges, perpendicular braces integral with said forwardly sloping inclined body portion, and the upper end portion of the first mentioned body member at opposite sides of said notches, and the first mentioned body member at opposite sides of the notch therein with upstanding flanges, said flanges being provided with slots and notches in the lower edges of the slots for accommodating a pivot member for a tool-head, and said body member and forwardly sloping inclined portion, respectively, at the inner ends of said notches being beveled to allow for maximum swinging movement of a tool-head.

SAM DIFIGLIA.
